UNITED STATES PATENT OFFICE.

REECE LAMB, OF PARIS, TEXAS.

SUSPENDED ROTARY FAN.

SPECIFICATION forming part of Letters Patent No. 689,098, dated December 17, 1901.

Application filed September 4, 1901. Serial No. 74,299. (No model.)

To all whom it may concern:

Be it known that I, REECE LAMB, a citizen of the United States of America, residing at No. 304 Bonham street, in the city of Paris, 5 in the county of Lamar and State of Texas, have invented certain new and useful Improvements in Suspended Rotary Fans, of which the following is a specification.

My improvement is directed to a construction of rotary fans of the suspended type whereby the usual suspending-brackets are dispensed with and the suspension of the fan-propelling shaft effected entirely within a depending tube within the interior of which the 15 fan-propelling gearing is arranged, rendering the device compact and utilizing the arrangement of the gear, whereby the gear itself is the means of bracing and steadyng the depending tube within which the fan-driven shaft is suspended. In these particulars the precise improvement will be set out in the claims hereto appended, in connection with the accompanying drawings, in which—

Figure 1 shows in section the rotary fan in 25 its use as suspended from the ceiling of a room. Fig. 2 shows in enlarged section that end of the depending tube in which the fan-carrying and rotating shaft is suspended and within which the gearing is arranged by 30 which the fan-shaft is rotated. Fig. 3 shows a like section of the lower end of the depending tube and the bearing therein of the fan-carrying shaft. Fig. 4 is a cross-section taken on the line $y-y$ of Fig. 2, showing the open 35 side of the depending tube for the arrangement therein of the gearing for rotating the fan-shaft. Fig. 5 shows a cross-section taken on the line $x-x$ of Fig. 2 and the ball-bearing cup by which the fan-shaft is suspended 40 within the depending tube. Fig. 6 shows in side view the tapering cup for the ball-bearings whereby the cups are firmly seated by being driven within the walls of the depending tube.

45 A tube 1, open at both ends, its end screw-threaded at 2, and having one side of its walls cut away so as to form an opening 3 in its circumference below its screw-threaded end, is screwed into a cap-plate 4, which 50 itself is firmly bolted to the ceiling or other support from which the tube depends, as in Fig. 1. Within this tube at each end is

seated a cup 5, not upon a shoulder on the walls of the tube, but driven in and firmly bound upon the walls. For this purpose the 55 cups are flaring, as in Fig. 6, so that in being driven in its walls are compressed, and thereby firmly bound within the tube, as in Figs. 2 and 3. The inner walls of the cups are concave to receive ball-bearings 6. Each 60 cup is centrally pierced to receive the fan-propelling shaft. At its upper end this shaft terminates in a screw end and has loosely fitted thereon a sleeve 8, adapted to form a suspending-seat for the shaft upon the balls. 65 At its lower end the shaft is reduced in diameter and is centrally supported at this reduced part 9 by the ball-bearings, as in Fig. 3.

While the ball-bearings and sleeve 8 form the suspending wear parts, a nut 10 on the 70 screw end of the shaft maintains the sleeve in place on the shaft and on the balls, so that the sleeve, the nut, and the shaft will rotate together upon the ball-bearings.

At its lower end the shaft which extends 75 outside of the tube has fixed thereon a screw-coupling 11, into which the fan-blades are screwed, while at its upper end below the cup-seat the shaft has fixed thereon a bevel-pinion 12, which, as seen, is within the de- 80 pending tube.

For rotating the suspended shaft under a high speed a large bevel-gear 13 engages the bevel-pinion 12 and for this purpose stands within the opening 3 in the wall of the de- 85 pending tube. The shaft 14, which carries this large bevel-gear, is mounted in hangers 15, depending from the ceiling, and which are provided with ball-bearings.

A spring-motor 20 may be used to drive the 90 horizontal shaft; but the arrangement of the latter, its gear within the side opening of the depending tube and the shaft-driving pinion also within the tube, makes the latter the hanger for the fan-shaft, the closure for said 95 shaft, and the closure for the gear by which the shaft is rotated. This is a feature of my improvement.

It will be noted that the shoulders 16 16 of the power-driven shaft by their engagement 100 with the hangers prevent endwise movement of the shaft. It will also be noticed, looking at Figs. 1 and 2, that the gear of this shaft may be made to engage, by the retaining-plates

17 at its circumference, with the depending tube at the ends of its opening 3, so that the firmly-supported gear within the side opening of the tube, in connection with the engagement of this gear with the gear on the fan-shaft, will have the effect of bracing the tube lengthwise and preventing sway and undue wear on the gear by holding it in close and uniform engagement. A screw 18 secures the 10 pinion on the fan-shaft.

In assembling the parts the fan-shaft is inserted through the openings in the cups, the tube is inverted, and the shaft moved out to allow the balls to be placed into the cup around 15 the reduced part 9 of the shaft. The latter is then drawn into the tube to seat the ball-bearings, as in Figs. 1 and 3. The ball-bearings are then placed into the upper cup, the sleeve 5 put on the shaft upon the balls, and 20 the nut 10 driven upon the sleeve. The tube is then screwed into the screw-cap plate 4. The power-driven shaft is then mounted and its gear engaged with the fan-suspending gear. Obviously the engagement of the large 25 gear at diameter points 17 with the ends of the opening in the side of the tube may be made in any suitable manner, as by extensions from the tube itself, and in erecting the fan its parts may be assembled in any convenient way.

I claim—

1. In a rotary fan, the combination of the tubular hanger having cup-seats and ball-

bearings therein at each end and a side opening below the upper cup-seat, with a fan-shaft, 35 means for suspending its upper end within the hanger, a bevel-gear on the shaft within the hanger below such suspending means, a horizontal shaft having a bevel-gear mounted to rotate within the open side of the hanger 40 and engaging the bevel-gear of the fan-shaft, and means for driving the horizontal shaft.

2. In a rotary fan, the combination of the tubular hanger having an opening in its side wall below its point of suspension, a bevel-gear on the shaft within the hanger below 45 such suspending means, a horizontal shaft having a bevel-gear mounted to rotate within the open side of the hanger and engaging the bevel-gear of the fan-shaft, plates or braces 50 at each end of the hanger-opening engaging the outer side of the power-driven gear whereby to brace the hanger and maintain the engagement of the gear, and means for driving the power-driven shaft. 55

3. In a rotary fan and in combination with a tubular hanger, having a side opening, a fan-shaft suspended entirely within said hanger, and bevel-gear arranged within the hanger at its side opening for rotating the fan-shaft. 60

In testimony whereof I affix my signature in presence of two witnesses.

REECE LAMB.
